DESIGN FOR A FOLDING CIGARETTE TRAY

Ernest Steiner, New York, N. Y.

Application February 12, 1938, Serial No. 75,104

Term of patent 7 years

To all whom it may concern:

Be it known that I, Ernest Steiner, a citizen of the United States and residing at New York city, in the county of New York and State of New York, have invented a new, original, and ornamental Design for a Folding Cigarette Tray, of which the following is a specification, reference being had to the accompanying drawing, forming part thereof, and in which

Fig. 1 is a top perspective view of a folding cigarette tray, showing my new design in open position.

Fig. 2 is a side sectional view of the tray upon the line 2—2 of Fig. 1 upon a somewhat enlarged scale as compared to Fig. 1 showing the tray in open position.

Fig. 3 is a fragmentary transverse sectional view upon the line 3—3 of Fig. 1 and,

Fig. 4 is a top perspective view of the tray in closed position.

The design is characterized by a folding cigarette case of the configuration shown, in which each of two oppositely disposed hinged tray-like members are provided with a plurality of parallel recesses extending toward each other on opposite sides of a transversely disposed hinged connection between the tray-like members.

I claim:

The ornamental design for a folding cigarette tray, substantially as shown and described.

ERNEST STEINER.
